UNITED STATES PATENT OFFICE.

EMILE MOREL, OF LIMOGES; HAUTE-VIENNE, FRANCE; ASSIGNOR TO G. A. GAGER & COMPANY, OF NEW YORK, N. Y.

DESIGN FOR THE ORNAMENTATION OF PLATES.

SPECIFICATION forming part of Design No. 18,989, dated April 2, 1889.

Application filed February 23, 1889. Serial No. 300,955. Term of patent 7 years.

To all whom it may concern:

Be it known that I, EMILE MOREL, a citizen of the Republic of France, residing at Limoges, France, have invented and produced a new and original Design for the Ornamentation of Plates, of which the following is a specification, reference being had to the accompanying photograph, which is a face view of my newly-designed plate.

The leading feature of my design consists in a spray, A, of conventional leaves and flowers on the face of the plate, representing the

passion-flower. The face of the plate is further ornamented by another spray, B, of conventional leaves and flowers, also representing the passion-flower. 15

I claim—

The design for the ornamentation of a plate, substantially as shown.

EMILE MOREL.
